UNITED STATES PATENT OFFICE

119,940

DESIGN FOR A HAND MIRROR FRAME OR THE LIKE

Alfred F. Reilly, North Attleboro, Mass., assignor to Evans Case Company, a corporation of Massachusetts

Application March 5, 1940, Serial No. 90,695

Term of patent 3½ years

To all whom it may concern:

Be it known that I, Alfred F. Reilly, a citizen of the United States, residing at North Attleboro, county of Bristol, and State of Massachusetts, have invented a new, original, and ornamental Design for a Hand Mirror Frame or the like, of which the following is a specification, reference being had to the accompanying drawing, forming a part thereof.

In the accompanying drawing Figure 1 is a plan view of a hand mirror frame showing my new design. Fig. 2 is a side view of a hand mirror frame showing my new design.

The side of the article illustrated not shown is conventional.

The dominant feature of the invention resides in the ornamentation on the back and handle portions.

I claim as my invention:

The ornamental design for a hand mirror frame or the like, as shown and described.

ALFRED F. REILLY.
